R. S. Wise

BY Victor J. Evans

ATTORNEY

WITNESS:

UNITED STATES PATENT OFFICE.

CHARLIE A. JAMESON, OF FRANKLIN, NEBRASKA.

ROSETTE.

Application filed September 30, 1925. Serial No. 59,663.

This invention relates to electric fixtures and has especial reference to ceiling rosettes for supporting drop lights, cords and so forth.

5 An object of the present invention is to provide means for securing the cord of a drop light or other electric device to a rigid portion of the rosette so as to prevent trouble due to faulty connections where the 10 cord is carried by a spring or yieldable contact.

Another object of the invention is the provision of novel means for securing the cap to the base of a rosette and for utilizing 15 the securing means to provide a path for the current and for attaching the conductor cord for the drop.

With the above and other objects in view, the invention further includes the following 20 novel features and details of construction, to be hereinafter more fully described, illustrated in the accompanying drawings and pointed out in the appended claim.

In the drawings:—

25 Figure 1 is an elevation with parts broken away showing a rosette constructed in accordance with the invention.

Figure 2 is a bottom plan view of the base of the rosette.

30 Figure 3 is a plan view of the cap showing the face of the cap opposed to the base.

Figure 4 is a sectional view taken substantially on the line 4—4 of Figure 2.

35 Figure 5 is an edge view of the cap partly broken away.

Referring to the drawings in detail wherein like characters of reference denote corresponding parts, the reference character 10 indicates the base of a rosette while 11 40 indicates the cap, both of which are made of suitable insulating material.

The base is provided upon its opposite faces with depressions 12 and 13 for the accommodation of various parts of the rosette 45 as will be hereinafter apparent, while the cap is provided with an annular shoulder 14 which extends within the recess 13. The cap is further provided with a depression 15 and an opening 16, both of which accommodate the conductor cord 17.

The base 10 is further recessed as indicated at 18 and secured within these recesses by attaching screws 19 are metallic angle

arms 20. The outer ends of these arms carry 55 angularly disposed hooks 21 which are adapted to be engaged by the offset or angular extremities 22 of angle arms 23. The inner ends of the arms 22 are secured to the cap 11 by screws 24 and by inserting the hooked ends 60 22 of the arms 23 within the recesses 18 and moving the cap in a rotary direction, the angular extremities 22 of these arms will engage the hook portions 21 of the arms 20 and provide an overlapping or interlocking 65 connection between the cap and base.

The angular arms 20 are provided at their ends opposite the hooks 21 with right angled extensions 25 which carry binding screws 26 and these screws provide means for attaching 70 the ends of conductor wires 27. The wires 27 lead from a suitable source of current through spaced openings 28 formed in the base. Additional openings 29 are provided in the base for the passage of screws 75 or like fastening devices whereby the base may be secured in place. Secured to the arms 20 as indicated at 30 are spring fingers 31. The free ends of these fingers extend within the recesses 18 and when the hooks 80 21 and the right angled extremities 22 of the connecting arms 20 and 23 are engaged, these spring fingers will contact with the arms 23 as shown in Figure 1 of the drawings and hold the said arms 20 and 23 engaged. The 85 cap 11 will thus be yieldingly held against rotary movement and the rosette assembled.

The angle arms 23 are provided with binding screws 32 which are designed to have attached thereto the terminal ends 33 of the 90 drop cord 17, so that this cord will extend from a firm and rigid support and will not exert a tendency to separate or destroy electric connection between the cap and base as frequently occurs where the drop cord is 95 attached to spring or yieldable contacts.

The invention is susceptible of various changes in its form, proportions and minor details of construction and the right is herein reserved to make such changes as properly fall within the scope of the appended claim. 100

Having described the invention what is claimed is:—

A rosette comprising an attaching base, 105 a cap, spaced base carried contacts each comprising a substantially U-shaped member secured to the base, means at one end of said

member for connection with an electric conductor, an engagaing hook extending inwardly from the other end of said member, a spring finger having one end secured to the 5 U-shaped member and its opposite end overlapping and normally engaging the hook, a contact arm secured to the cap and extend-

ing parallel with the axial center thereof and a hook at the outer end of the contact arm for engagement over the engaging hook 10 between the last mentioned hook and the spring finger.

In testimony whereof I affix my signature.

CHARLIE A. JAMESON.
